CLAIM

I claim the ornamental design for a design for a handheld scanning device, as shown and described.

DESCRIPTION

FIG. 1 is a front perspective view of the handheld scanning device;

FIG. 2 is a top view of the handheld scanning device of FIG. 1;

FIG. 3 is a right side view of the handheld scanning device of FIG. 1;

FIG. 4 is a left side view of the handheld scanning of FIG. 1;

FIG. 5 is a front view of the handheld scanning device of FIG. 1;

FIG. 6 is a back view of the handheld scanning device of FIG. 1; and,

FIG. 7 is a bottom view of the handheld scanning device of FIG. 1.

The portions shown in broken line are not claimed.
